UNITED STATES PATENT OFFICE.

EMMANN BACH, OF WOONSOCKET, RHODE ISLAND.

SELF-OPENING KNUURLING TOOL.

1,422,649.

Specification of Letters Patent. Patented July 11, 1922.

Application filed July 25, 1921. Serial No. 487,335.

To all whom it may concern:

Be it known that EMMANN BACH, a citizen of the United States, and a resident of Woonsocket, in the county of Providence, State of Rhode Island, have invented certain new and useful Improvements in Self-Opening Knurling Tools, of which the following is a specification.

The fundamental object of this invention is to provide a knurling-tool device, of the self-opening type, by the use of which time will be saved in performing the operation of knurling, as compared with other forms of knurling-tools. Whereas, with the ordinary tool, it is necessary to feed forward and back slowly over the work, my tool completes the knurl in passing once over the work, automatically opening at the desired point, and being quickly withdrawn, thereby saving the time usually required for feeding back, and avoiding the possibility of "cross-knurling," common to other tools. The construction of my tool is such that, by locking it at the desired point, it may be advantageously used where it is desired to start the knurl some distance from the end of a piece,—which is impossible in the use of other tools with which I am familiar.

The accompanying drawing clearly shows an exemplary construction capable of carrying out the underlying principles of the invention. Like reference characters denote corresponding parts throughout the several views. Briefly described:

Figure 1 is an end view of the device; Figure 2 is a view in top plan, partly in section, of the device; Figure 3 is a view in side elevation, partly in section, of the device. Referring, now, in detail to the drawing:

A designates the chuck of a hand screw, single-spindle automatic, or like machine, B the piece or work to be knurled, and C an adjustable tripper, or knock-off rod, suitably carried by the machine, for the purpose hereinafter appearing.

D is the shank of the knurling device, which shank is held rigidly in the turret of the screw machine, and is integral with a head, D', having a reduced concentric neck, D², bearing at one end, d, against an end plate or disk O, having a concentric, circular, central aperture, o, fitting the shank, D. The head, D', is provided with a longitudi-

nally-extending, concentric bore, d', for the reception of the work B in the operation of the device. The end plate or disk, O, and the neck, D², are suitably detachably secured together, as by screws, d''.

K designates a rotatable cam-ring, which may be of the same diameter as the disk or end plate, O, and which is adapted to bear, at one end thereof, against said disk. The cam-ring encircles the neck, D², of the head, D', and is provided with a circumferential cam-groove, k, for the purpose presently appearing. The cam-ring may be provided, on its periphery, with a radially-projecting handle, N.

Suitable means may be provided for limiting the degree of rotatable movement of the cam-ring, K, on the neck, D²; in this instance, complementary, co-acting stop-pins I, J, are, respectively, eccentrically carried by the ring, K, and the plate, O.

Suitable means are provided for automatically rotating the cam-ring,—in this instance, a spring-motor, comprising a coiled spring, U, is disposed in the recessed portion, n, of the cam-ring, K, and is operatively associated with said ring and with the disk O, so as to turn the cam-ring, as more fully hereinafter appearing in the description of the operation of the device.

Seated in diametrically oppositely disposed, radial recesses, d₂, in the head, D', and having a limited tilting movement therein, are levers, L, L, mounted for tilting movement on pins, d³, carried by the head, D', and extending transversely across said recesses. Each of said levers has a lateral head, l, in which is disposed a knurling-roller, T. Collar-screws, S, serve to adjust the rollers for different diameters of work, within its range; and, by means of set-screws, Q, co-operating with V-shaped notches in the shanks of the roller-holders, R, adjustment may be made for making any type of knurl, either square, diamond-shaped, spiral, or straight.

Each of the levers, L, is provided with a lateral projection or toe, l', into and out of contact with which rides the cam-surface or track, k, of the cam-ring K.

Co-operating with each lever, L, is a leaf spring M seated in a longitudinally-extending, peripheral groove, m', in the neck, D₂, of the head, D'. Each leaf spring is suitably

secured, at one end, as by means of a screw, *m*, to the neck, *D*², and is seated, at its other end, in a notch, *l*², in the lever, *L*. The tendency of the leaf springs is to tilt the levers, *L*, in a direction to lift the knurling rollers, *T*, clear of the work, *B*.

To bring the rollers, *T*, into operative position with respect to the work, *B*, it is necessary to turn the cam-ring, *K*, to bring the proper portion of the cam-surface or track, *k*, of the cam-ring into contact with the toes, *l*¹, of the levers, *L*, which portion of the cam-track functions to tilt the levers, against the influence of the springs, *M*, to move the rollers, *T*, toward and into contact with the work, *B*. In this movement of the cam-ring, the cam-spring, *U*, is compressed.

Suitable means are provided for releasably locking the cam-ring in the position just referred to, with the spring, *U*, compressed. In this instance, a latch, *F*, is provided, which is mounted for tilting movement on a pivot-pin, *f*, carried by the head, *D*¹. The latch is seated in a peripheral recess, *f*¹, in the head, *D*¹, and is provided with a toe, *f*², which is adapted, in the locking position of the cam-ring, *K*, to seat in a peripheral notch or groove, *G*, in the cam-ring, *K*, thereby holding the latter against rotation. A curved leaf-spring, *f*³, beneath the latch serves to hold it in operative position.

E designates a bell-crank lever, fulcrumed at *e* in the recess, *f*, the shorter arm of the lever having a knuckle, *e*¹, engaging a correspondingly-shaped recess, *e*², in one end of the latch, *F*.

The adjustable relatively stationary tripper, *C*, is arranged in the path of movement of the longer arm of the bell-crank lever, *E*, so that, in the movement of the tool-device, said longer arm strikes against the free end of the tripper, which rocks the bell-crank lever on its fulcrum, thus tilting the latch, *F*, to move the toe, *f*² thereof out of locking engagement in the groove, *G*, whereupon the spring motor, *U*, functions to rotate the cam-ring, *K*, in the direction of the arrow in Fig. 1, through an arc of about 20°. The cam-track, *k*, during this movement of the cam-ring, releases its engagement with the toes, *l*¹, of the levers, *L*, whereupon the leaf-springs, *M*, function to rock said levers on their fulcrums, thereby moving the rollers, *T*, *T*, out of contact with the work, *B*.

The device may be locked in operative position for knurling, by hand or otherwise, as desired.

While the device, as shown, is essentially for use on a hand-screw, or single-spindle automatic, where the work revolves, it can obviously be modified for use on a six-spindle automatic or like machine, in which the tool rotates.

It will be seen that the device automatically opens at the desired point, and may be

quickly withdrawn, thereby saving the time required for feeding back and avoiding the possibility of "cross-knurling" which characterizes other tools.

Having thus fully described my invention, 70 what I claim as new and desire to secure by Letters-Patent is:

1. A self-opening knurling-tool device, comprising a shank adapted to be held rigidly in the turret of a screw-machine, tilt- 75 able, knurling-tool holding members carried by said shank, spring means also carried by said shank and engaging said members to tilt the tool-holding ends of the latter away from the work, a cam-member carried by 80 said shank and engageable with said tool-holding members to tilt the tool-holding ends of the latter toward the work, and a spring operatively associated with said shank and said cam-member for moving said 85 cam-member to release said tool-holding members.

2. A self-opening knurling-tool device, comprising a shank adapted to be held rigidly in the turret of a screw-machine, tilt- 90 able, knurling-tool holding members carried by said shank, spring means also carried by said shank and engaging said members to tilt the tool-holding ends of the latter away from the work, a rotatable cam-ring carried 95 by said shank and engageable with said tool holding members to tilt the tool-holding ends of the latter toward the work, and a spring motor operatively associated with said shank and said cam-ring for moving the latter to release said tool-holding members.

3. A self-opening knurling-tool device, comprising a shank adapted to be held rigidly in the turret of a screw-machine, tilt- 105 able knurling-tool holding members carried by said shank and having lateral toes, springs carried by said shank and engaging said members to tilt the tool-holding ends thereof away from the work, a rotatable cam-ring carried by said shank and having a cam-track engageable with said tool-holding members to tilt the tool-holding ends of the latter toward the work, and a spring motor operatively associated with said shank and cam-ring for moving the latter 110 to release said tool-holding members.

4. A self-opening knurling-tool device, comprising a shank adapted to be held rigidly in the turret of a screw-machine, tilt- 120 able knurling-tool holding members carried by said shank, springs also carried by said shank and engaging said members to tilt the tool-holding ends thereof away from the work, a rotatable cam-ring carried by said shank and engageable with said tool-holding members to tilt the tool-holding ends thereof toward the work, a spring motor operatively associated with said shank and said cam-ring for moving the latter to release 125 said tool-holding members, and a latch car- 130

ried by said shank and engageable with said cam-ring to hold the same against rotation under the influence of said motor.

5. A self-opening knurling-tool device, comprising a shank adapted to be held rigidly in the turret of a screw-machine, tiltable knurling-tool holding members carried by said shank, springs also carried by said shank and engaging said members to tilt the 10 tool-holding ends thereof away from the work, a rotatable cam-ring carried by said shank and engageable with said tool-holding members to tilt the tool-holding ends there-

of toward the work, a spring motor operatively associated with said shank and said cam-ring for moving the latter to release said tool-holding members, a tiltable latch fulcrumed on said shank and engageable with said cam-ring to hold the same against rotation under the influence of said motor, 20 and a tripping-member pivoted to said shank and engaging said latch for tilting the same to release said cam-ring.

In testimony whereof I hereunto affix my signature.

EMMANN BACH.
